(57) **CLAIM**

The ornamental design for a pair of symmetrically shaped mirrored image self-adhesive printable labels with corresponding matched inner and outer cropped edges with detachability and optional perforated central fold, as shown and described.

DESCRIPTION

FIG. 1 is a top plan view of a pair of symmetrically shaped mirrored image self-adhesive printable labels with corresponding matched inner and outer cropped edges with detachability and optional perforated central fold showing my new design which is shown broken away to indicate indeterminate width. The adhesive surfaced bottom view is identical thereto;

FIG. 2 is a folded symmetrical, or optional, detached singular top plan view thereof;

FIG. 3 is a top plan view thereof, shown broken away to indicate indeterminate length;

FIG. 4 is a folded symmetrical, or optional, detached singular top plan view of FIG. 3;

FIG. 5 is a top plan view of a second embodiment of my new design which is shown broken away to indicate indeterminate width. The adhesive surfaced bottom view is identical thereto;

FIG. 6 is a folded symmetrical, or optional, detached singular top plan view of FIG. 5;

FIG. 7 is a top plan view of FIG. 5, shown broken away to indicate indeterminate length; and,

FIG. 8 is a folded symmetrical, or optional, detached singular top plan view of FIG. 7.
